UNITED STATES PATENT OFFICE.

HUBERT W. MORGAN, OF MERIDEN, CONNECTICUT.

DESIGN FOR A PENCIL.

SPECIFICATION forming part of Design No. 22,989, dated December 26, 1893.

Application filed September 16, 1893, Serial No. 485,723. Term of patent 7 years.

To all whom it may concern:

Be it known that I, HUBERT W. MORGAN, of Meriden, in the county of New Haven and State of Connecticut, have invented certain new and useful Improvements in Designs for Pencils; and I do hereby declare the following to be a full, clear, and exact description of the invention, such as will enable others skilled in the art to which it pertains to make and use it, reference being had to the accompanying drawings, which form part of this specification.

My invention relates to a new and original design for pencils of which the following is a full specification, reference being had to the accompanying drawings which form a part thereof.

Figure 1 is a perspective view of a pencil which embodies my design. Fig. 2 is a cross section on line $z-z$ of Fig. 1. Fig. 3 is a cross section on line $x-x$ of Fig. 1. A, indicates the pencil which is provided

with a flat portion E extending from at or near the point to the opposite end thereof. The balance of the pencil from side to side of the flat portion is made rounding and tapers in one direction from the point B to the head, and in the opposite direction from the same point, to or near the point or writing end of the pencil.

The leading feature of my design consists in a flat portion E applied to a pencil tapered as shown and described.

Having thus described my design, what I claim, and desire to secure by Letters Patent, is—

The design for a pencil substantially as herein shown and described.

In testimony whereof I affix my signature in presence of two witnesses.

HUBERT W. MORGAN.
